UNITED STATES PATENT OFFICE.

ERNEST F. PFLUEGER, OF AKRON, OHIO.

DESIGN FOR A PAPER-FASTENER.

SPECIFICATION forming part of Design No. 31,842, dated November 14, 1899.

Application filed October 20, 1899. Serial No. 734,278. Term of patent 14 years.

To all whom it may concern:

Be it known that I, ERNEST F. PFLUEGER, a citizen of the United States, residing at Akron, in the county of Summit and State of Ohio, have invented and produced a new and original Design for Clasps or Fasteners, of which the following is a specification, reference being had to the accompanying drawings, forming part thereof.

10 Figure 1 is a plan view of my fastener; and Fig. 2 is a section on the line $x x$, Fig. 1.

This invention has relation to a certain new and original design for a clasp or fastener; and it consists in the novel form and configuration thereof, as hereinafter described, and illustrated in the accompanying drawings.

15 The leading feature of the design consists

in a wire clasp having two elongated loops lying one within the other and formed with corrugated or waved sides, the inner loop being connected to the outer one by a narrow open neck portion.

20 In the accompanying drawings, A designates the outer loop, B the inner one, and C the connecting open neck portion.

25 What I claim is—

The design for a clasp or fastener substantially as herein shown and described.

In testimony whereof I affix my signature in presence of two witnesses.

ERNEST F. PFLUEGER.

Witnesses:

T. W. WAKEMAN,

H. D. HOSKIN.
